UNITED STATES PATENT OFFICE.

ANDREW CAMPBELL, OF BROOKLYN, ASSIGNOR TO JOHN McLOUGHLIN AND EDMUND McLOUGHLIN, OF NEW YORK, N. Y.

PRINTER'S INKING AND DISTRIBUTING ROLLER.

SPECIFICATION forming part of Letters Patent No. 280,447, dated July 3, 1883.

Application filed December 14, 1882. (No model.)

To all whom it may concern:

Be it known that I, ANDREW CAMPBELL, a citizen of the United States, residing in Brooklyn, Kings county, New York, have invented 5 certain Improvements in Printers' Inking and Distributing Rollers, of which the following is a specification.

This invention relates to a roller for inking forms, whether on stone or in type, and also 10 for distributing the ink for the form-rollers. It is intended to take the place of the ordinary leather and composition rollers used for these purposes.

The ordinary composition-rollers, molded 15 from a compound of glue and a saccharine substance, have many objectionable features, arising partly from their susceptibility to changes of temperature and hygrometric changes, and partly from failure to properly perform their 20 functions, even under the best conditions. Notwithstanding these defects, however, such composition-rollers have, up to this date, served the purposes of the printer in general better than any other class of rollers, so far as I am aware. The compound leather and rubber 25 rollers proposed for printers' use have also many objectionable features, which I seek to avoid in my herein-described roller, which belongs to this class. My object is to provide a 30 light roller with a flexible, uniform, and elastic surface, and free from the various defects inherent in the rollers in ordinary use.

For the stock of my roller, I prefer to employ a metal cylinder which may be solid or 35 hollow. Around this I tightly wrap a sheet of fabric, preferably linen or muslin, covered on one or both sides with soft india-rubber prepared for vulcanization, or some rubber compound of a yielding character. This wrapping 40 is continued until the proper thickness is attained—say one-fourth of an inch, or less. Over this I apply a uniformly thick layer of soft rubber or rubber compound prepared for vulcanization to serve as a cushion. Over 45 this cushion I wrap one or more thicknesses of some fabric, preferably fine wire-gauze or strong linen. One thickness will usually be enough. Over this wrapping I apply another layer of rubber or rubber composition prepared 50 for vulcanization. This layer need not be

so thick as the cushion-layer, as it is intended for a "facing" layer. The core thus formed is now subjected to the usual process of vulcanization, whereby the rubber is hardened to the proper degree, and all the layers and wrappings are firmly cemented together. I now 55 true up the core by dressing or grinding off the surface of the exterior vulcanized layer until it is perfectly cylindrical and true on the spindles or bearings of its stock, and has a 60 perfectly true surface. I now cover the core with some thing, substance, or composition that will protect the rubber of the roller from the action of the oils and solvents found in 65 printer's ink. For this purpose I may employ several methods. I may cover the roller with 70 a sheet of tissue-paper saturated with paraffine; or I may coat it with a varnish that will resist the solvents in the ink; or I may japan it as metals are japanned. I prefer, however, 75 to first coat it with such japan as is employed in the manufacture of patent-leather. Then, before the japan is dry, I wrap the roller with a single layer of fine linen or muslin. Then I apply another coat of japan, and, before it is 80 dry, slip on the final covering of leather, which forms the exterior surface of the finished roller. The roller thus prepared is then carefully stoved to bake the japan, and the leather will be found firmly fixed in place. The japan 85 will effectually protect the rubber from the solvents in the ink. I may omit the textile or other fabric, and rely wholly upon the japan.

In the drawings which serve to illustrate my invention, Figure 1 is a longitudinal mid-section of a portion of a roller constructed according to my invention, and Fig. 2 is a cross-section of the same.

I have not deemed it necessary to show the ends of the roller, as they may be constructed 90 in the usual or any good way.

A is the cylindrical stock. B is the wrapping of rubber-covered fabric. C is the rubber cushion-layer. D is the wrapping of gauze, linen, or other similar material. E is 95 the facing layer of rubber. F is the interposed protecting film or covering, and G is the exterior leather covering.

I prefer to employ for the leather covering G a leather that has been thoroughly tanned 100

by a slow process, and which is about one-eighth of an inch in thickness when shaved and finished. The hair or grain side of the leather is arranged outwardly to receive the 5 ink, by preference; but either side may be arranged exteriorly. This leather is uniformly flexible, and is especially suited to my purposes.

The object of the gauze or textile layer D is 10 to give the roller that rigidity which prevents distortion from its true cylindrical form when rolling over the type or stone, and prevents the "creeping" due to the expanding by pressure of the part of the roller in contact with the 15 form. At the same time it does not impair the elasticity of the roller.

I may in some cases omit the wrapping B from the stock and apply the cushion of rubber directly to the same; or I may substitute 20 a wrapping of some other kind—as covered wire, for example. The purpose of this wrapping is to give to the cushion a firmer hold on the stock and prevent it from tearing loose, as it is liable to do where the cushion is applied 25 to the stock.

The leather covering of the roller, when applied with japan and baked, forms substantially one with the core of the roller, and this means of attachment may be employed with 30 rollers having cores constructed differently from that herein described.

By "rubber compounds," I mean compounds of an elastic or yielding nature of which rubber forms a part. Many compounds of this 35 nature are well known in the arts.

Having thus described my invention, I claim—

1. A roller to be employed in printing for applying and distributing ink, comprising a

stock, a cushion of rubber or its specified 40 equivalent on said stock, a textile covering over said cushion, a facing layer of rubber or its specified equivalent over said textile covering, an interposed film or substance, substantially as described, to protect the rubber 45 from the solvents in the ink, and an exterior covering of leather, all constructed and arranged substantially as set forth.

2. A roller for use in printing, having a core 50 with a rubber face, and an exterior covering of leather, and an interposed layer of japan between the rubber facing and the leather, said japan being baked in the usual way to form a protecting-shield to prevent the solvents in the ink from injuring the rubber, substantially as set forth.

3. The combination, to form a roller for use 55 in printing, of a core, A, a wrapping, B, a cushion of rubber, C, a textile covering, D, a rubber facing layer, E, an interposed protecting-covering, F, for the facing, constructed and applied substantially as described, and an exterior covering of leather, G, all arranged substantially as described.

4. A roller for printers' use, comprising a 60 stock, a rubber cushion or core, a leather cover, and a layer of cement between the rubber and the leather, which will not be affected by the ink, whereby the said rubber is protected against injury from the ink, substantially as set forth.

In witness whereof I have hereunto signed my name in the presence of two subscribing witnesses.

ANDREW CAMPBELL.
